UNITED STATES PATENT OFFICE.

WILLIAM J. KEENE, OF CHICAGO, ILLINOIS, ASSIGNOR TO CHICAGO SPRING HINGE COMPANY, OF CHICAGO, ILLINOIS, A CORPORATION OF ILLINOIS.

SPRING HINGE.

Application filed April 21, 1924. Serial No. 707,823.

To all whom it may concern:

Be it known that I, WILLIAM J. KEENE, a citizen of the United States, and a resident of Chicago, county of Cook, and State of Illinois, have invented certain new and useful Improvements in Spring Hinges, of which the following is a specification.

My invention relates to hinges and has reference more particularly to spring hinges of the double-acting type.

The principal objects of my invention are to permit double-acting spring hinges to be mounted directly on the door jamb or other support without requiring a jamb strip or filler block; to construct the hinge so that a center of standard form may be used, thus obviating the necessity of making up a special center and also avoiding weakness which would result if the center were formed with offset portions; to relieve strain on the center by providing an abutment against which the free end of the center engages when the door swings on that end of the center; and in general, to adapt the present standard types of double-acting spring hinges for mounting directly on the door jamb or other support, without a jamb strip or filler block, by simple changes in the jamb leaf and door leaf which serve to increase the strength of the hinge.

On the drawings:

Fig. 1 is a top view of a hinge constructed in accordance with my invention, together with fragmentary portions of the door and door jamb, and shows the door in the closed or central position;

Fig. 2, a similar view showing the door swung to the right;

Fig. 3, a similar view showing the door swung to the left;

Fig. 4, a rear view of the door leaf and fragmentary portion of the center; and

Fig. 5, a view, partially in section, taken on the line 5—5 of Fig. 2.

Referring to the drawings, the reference numeral 1 indicates a hinge center which may be of any standard type, for example, as shown and described in my Patent No. 918,882, dated April 27, 1909, said center being of elongated form and provided with tubular barrels 2 and 3 respectively along the lateral edges. Each barrel has a plug 4 secured in the upper end by riveting or in any other convenient manner to prevent

relative turning movement of the barrel and plug and has a reduced extension 5 which is encircled by the upper end of a spring 6 and provided with a notch 7 in the side to interlock with the inturned end 8 of the 60 spring. Each barrel also has a plug 9 fitted to turn in the lower end thereof, a bushing 10 being preferably interposed between the barrel and plug, and this plug likewise has a reduced extension 11 in the barrel which 65 is encircled by the lower end of the spring 6 and provided with a notch 12 to interlock with the inturned lower end 13 of the spring. The plugs 4 and 9 are bored out axially to receive a pin 14 which extends 70 through the barrel, and the pin has a head 15 fixed on one end and is threaded at the other end to receive a nut or detachable head 16.

The jamb leaf of the hinge is indicated at 75 17 and comprises a flat plate with out-turned ears 18 at the upper and lower extremities which are apertured to receive the pin 14, and the upper ear is interposed between the head 15 of the pin and the 80 upper plug 4, while the lower ear 18 is interposed between the nut or removable head 16 and the plug 9. The plug 9 is provided at intervals therearound with radial holes or seats 19 for a pin 20 which is 85 adapted to engage the edge of the jamb leaf 17 as shown in Fig. 2. In practice, the plug 9 is turned by means of a suitable tool until the spring 6 is placed under the desired tension, after which the pin 20 is inserted in 90 the proper hole 19 to engage the plate 17 and maintain the spring tension which serves to swing the center inwardly to a position parallel with the jamb leaf 17 as shown in Fig. 1.

The door plate, which is indicated at 21, is formed with the wings or flanges 22, bent laterally at the upper and lower ends, which embrace the center 1 therebetween and are of suitable width to extend to the surface 100 of the door jamb 23 when the door leaf 21 lies against the outer surface of the center 1, as shown in Fig. 1. These wings or flanges 22 are extended beyond the plate 21 and are offset outwardly as shown in Figs. 1 105 and 2, to form ears 24 at the corresponding ends whereby the door leaf is hinged to the free end of the center 1. These ears are apertured to receive the pin 14 of the barrel 3 and the upper ear is interposed be- 110

tween the head 15 of said pin and the plug 4 and the lower ear between the nut or removable head 16 and the plug 9. This plug 9 in the barrel 3 is the same as the correspondingly numbered plug in the other barrel 2 and has the radial holes or seats to receive the pin 25 which engages the outward edge 26 of the door leaf 21 and holds the spring 6 in said barrel under a suitable tension for swinging the door leaf inwardly against the outer face of the center 1.

10 The jamb leaf 17 is secured directly to the surface of the jamb or other support 23 as shown by screws 27, and does not require any jamb strip or filler block as is the case of the usual forms of double-acting hinges, and the door which is shown at 28 is notched to a depth equal to the width of the flanges or wings 22 to receive the door leaf 21 therein, as shown by dotted lines in Figs. 1 and 2, so that the rear edge of the door comes close against the face of the jamb 23, as shown in Fig. 1, when the door is in the center position. The door leaf 21 is provided 25 with a number of countersunk screw holes in the usual manner to receive the screws 29 for fastening the door leaf to the door.

15 In double-acting hinges, the hinge center is subjected to considerable strain, particularly when the door is swung on the pivot at the free end of the center, owing to the fact that this pivot must be spaced a distance greater than the thickness of the door from the fixed pivot—that is, the pivotal axis of the center and jamb leaf. For the purpose of relieving this strain, I have extended the jamb leaf 17 as shown so that it projects under the barrel 3 to form an abutment against which the free end or barrel 20 3 of the center engages when the door is swung in the direction shown in Fig. 3. In the center position of the door, the barrel 3 is removed slightly from the plate 17 as shown in Fig. 1, owing to the engagement of 25 the rear edge of the door with the jamb 23, but a very slight swinging of the door from the center position toward the position shown in Fig. 3, brings the barrel 3 against the plate 17 and the latter serves as a brace 30 to avoid strain which is ordinarily imposed upon the center. It will be noted there is no turning movement of the barrel 3 as

the door is swung to the position of Fig. 3, and that therefore there is no rubbing action between the barrel and plate 17 and 55 the engagement thereof does not interfere with the freedom of movement of the hinge.

While I have shown and described my invention in a preferred form, I am aware that various changes and modifications may 60 be made without departing from the principles of my invention, the scope of which is to be determined by the appended claims.

I claim as my invention:

1. In a double-acting spring hinge, the 65 combination of a center comprising a pair of spaced parallel barrels connected by a web lying substantially in the plane of the axes of the barrels, a jamb leaf pivoted to one barrel and providing an abutment for 70 the other barrel to hold the web of the center away from the jamb leaf, and a door leaf pivoted to the last mentioned barrel so as to swing to a position between the barrels and adjacent the outer face of the web, said 75 door leaf having flanges at the ends straddling the web and the jamb leaf.

2. In a double-acting spring hinge, the 80 combination of a jamb leaf and door leaf and a center web interposed between the leaves, said jamb leaf and door leaf being pivoted at opposite sides of the center web, with the pivots substantially in line with the center web, a spring at each pivot, said jamb leaf having an attaching face lying 85 in a plane at one side of the springs, and interengaging means affording contact between the jamb leaf and a relatively movable portion of the hinge whereby the attaching face of the jamb leaf is held in 90 said plane at one side of the springs.

3. In a double-acting spring hinge, the 95 combination of a center comprising a pair of spaced parallel barrels connected by a web lying substantially in the plane of the axes of the bearings; a door leaf having a pivotal connection with one of the barrels and a jamb leaf hinged to the other barrel, said jamb leaf being extended to form a fulcrum for the aforesaid pivotal connection 100 when the door leaf is swung away from the center.

WILLIAM J. KEENE.
